UNITED STATES PATENT OFFICE.

J. H. HOWE AND CHARLES E. STEVENS, OF FULTON, NEW YORK, ASSIGNEES TO ARROW-HEAD MILLS INC., OF FULTON, NEW YORK, A CORPORATION OF NEW YORK.

METHOD AND APPARATUS FOR TREATING RAGS IN THE PRODUCTION OF PAPER STOCK.

Application filed February 17, 1921. Serial No. 445,875.

To all whom it may concern:

Be it known that J. H. Howe and Charles E. Stevens, of Fulton, in the county of Oswego, in the State of New York, have ⁵ invented new and useful Improvements in Methods and Apparatus for Treating Rags in the Production of Paper Stock, of which the following, taken in connection with the accompanying drawings, is a full, clear, and ¹⁰ exact description.

This invention relates to certain improvements in method and apparatus for treating rags in the production of paper stock.

Generally speaking, the broad objects of ¹⁵ the invention are to reduce the labor and cost of treating the rags in the production of paper stock, and to improve the character of such stock.

The common and usual method heretofore commercially used for handling the rags as received in bales, and the process followed until they are reduced to the form of paper stock consists in first running the rags through rag cutters, from which they ²⁰ are conveyed to a rag room, or rag storage. In this storage the cut rags are forked and raked by operators into a suitable measuring box, which is set in the floor.

This measuring box is of proper size to ³⁰ hold a beater load of rags. The bottom of the measuring box is usually a false bottom held with hinges which permit the contents of the box to be dumped, when desired, into a cart positioned preferably in the room beneath the box and the rag storage room. This cart is ordinarily wheeled by operators to the beater to be filled. When the cart reaches the front of the beater, one side of the cart, which is hinged, may be lowered ³⁵ so as to rest on the beater tub, and the contents of the cart are manually raked out into the beater.

The beater is filled with water, and the cut rags and its operation is continued until ⁴⁰ the contents are suitable to be pumped to the usual head box, from which they are fed to the Jordan engine.

This usual method of handling the rags requires a great deal of hand labor, viz: ⁵⁰ men in the rag room to fork the rags into the measuring box, from which they are discharged into the cart, and men in the beater room to wheel the cart back and forth and fork the contents of same into the beaters.

Further, the rags in being handled with ⁵⁵ forks and rakes are rolled up into balls, and when the same are fed into the beaters, it is necessary to raise the beater roll off the bed-plate. If this is not done, the beater roll will "jump" when balls of rags pass ⁶⁰ over the bed-plate, and damage to the machinery always results. In using the present commercial process, after the beater is completely filled, it is necessary to gradually lower the roll and run the beater for quite ⁶⁵ a considerable time previous to letting the roll down on the bed-plate and putting the same to work cutting rags.

Further, it is obvious that any metal ⁷⁰ which is in the rags is liable to get into any of the beaters so they must all be made of the most substantial materials to withstand these severe shocks. Furthermore, this metal if it gets into the beaters, will be discharged into the beater chests, and is liable ⁷⁵ to be carried along further and cause serious damage to the machinery.

Further, the old process creates a good deal of dust which is distributed not only ⁸⁰ throughout the rag cutting room, but also in the beater room.

Still further, it is well known in the art, that the beating of stock in felt mills requires cutting up the stock into fibres just as quickly as possible. The longer it takes ⁸⁵ to beat the stock, the poorer the sheet of paper, because many of the fibres in passing between the plates of the beater roll and the bed-plates, instead of being cut, are drawn out. This drawing of the fibres is distinctly a disadvantage in a felt mill, and any reduction in the time necessary to reduce the rags to finished stock improves the character of that stock, and we have discovered that whereas in the old process, in ⁹⁰ which the entire reduction of the rags to finished stock is effected in a single beater, the time required for that operation is not less than one hour (1 hr.) and usually requires additional time up to an hour and a half. ⁹⁵

The improved process of this application reduces the time required to produce finished stock to about 40 minutes. Further, it eliminates the labor of forking rags from storage piles, and discharging them from the measuring box into the cart. It eliminates also the labor of wheeling the cart and raking its contents into the beaters. ¹⁰⁰ ¹⁰⁵

Furthermore, metal which may be in the rags is confined to the half stock beaters, and the half stock chest, which necessitates constructing the half stock beaters in a substantial manner, but the finishing beaters need not be so heavily built, and will last indefinitely and require a great deal less attention than formerly.

These advantages are attained by the apparatus and process hereinafter described, in connection with the accompanying drawings, in which:—

Fig. 1 is a diagrammatic elevation of the apparatus of our invention.

Figs. 2 and 3 are respectively a top plan and a vertical section of the ordinary and well known beater, illustrating the improved method of discharging the rags into the beater by which balling up of the rags is avoided, and the necessity of raising the beater roll off the bed-plate during operation eliminated.

The apparatus as shown, comprises a rag-cutting room —1— containing one or more rag cutters —2— from which a gravity conveyor, or pipe —3— leads directly to the hood of a half-stock beater, or beaters —4—. As shown, these beaters are 2 in number, and the conveying pipe is provided with a valve —5—, permitting direction of the cut rags into either of the beaters in a substantially continuous uniform stream. The conveyor —3— penetrates the hood —6— of the beater so as to discharge the cut rags on the rapidly revolving beater-roll —7— so that the rags are broken up and scattered by the force of the roll. At the same time these cut rags are being fed into the half-stock beaters —4—, the beater tubs —8— are being filled with water. The beater roll may be kept in contact with the bed plate all the time that the beater is being filled. This is possible because the rags are fed into the beater so gradually in a constant, uniform stream, and they do not form into balls or thick masses, which would cause the beater roll to jump.

It is obvious that with this method the roll begins to work as soon as any rags are fed into the beater. These half-stock beaters —4— should be constructed of the most rigid material to withstand the severe shock due to any metal or other hard substance coming into the beaters with the rags.

These half-stock beaters —4— quickly break up the rags and reduce the same to a condition where they may be handled successfully by an agitator and a pump. The time required to reduce the rags to half-stock is found to be approximately 20 minutes. When the stock has arrived in this condition, the beaters are dumped, and the contents discharged by gravity into the half stock chest —9—. The stock in this chest is kept in a continual state of agitation, as by rotary agitator —10— and any heavy, undesirable

substances, such as metal, buttons, dirt, etc., settle to the bottom of the chest, which is provided with a suitable trap basin —11— to catch and retain the same until cleaned out.

From the half-stock chest —9—, the stock is pumped as required, preferably by a centrifugal pump —12— through pipe —13—, from which it is discharged under considerable pressure and with great force through the hoods —14— of the finishing beaters —15— and upon the beater rolls —7— of such beaters, further breaking up the stock, which at all times has a tendency to hang together in balls, or lumps.

In view of the fact that the contents of these finishing beaters —15— is solely rags and water, they can be constructed of less rigid material, and in a less expensive manner than the ordinary beaters used in the commercial process. The beater roll may be set down hard on the bed-plate and kept continuously at work. By keeping the rolls on the bed plate the stock is kept in a more uniform condition than is possible where the rolls are raised and lowered alternately as the beaters are filled and dumped.

By reason of the increased efficiency, it is found that the half stock can be reduced to finished stock in these finishing beaters in approximately 20 minutes, thus effecting a saving in time of at least 20 minutes in producing finished stock, and very often the time saved is considerably greater with the corresponding resultant improvement in the character of the product. When the stock in the finishing beaters has been reduced to the proper consistency, these beaters are dumped and the contents discharged by gravity into the beater chest —16—, also provided with a rotary agitator —17— and a catch basin —18—.

The stock from the beater chest —16— is pumped preferably by a triplex plunger pump —19— to the head box —20—, from which it is discharged by gravity to the Jordan engine —21—. Any excess stock which is pumped to the head box may overflow back into the chest —16— through pipe —22—.

After the stock passes through the Jordan engine —21— it is discharged into the machine chest —23— which is also equipped with an ordinary rotary agitator —24—.

From this chest the stock is pumped in the usual manner to the screen, and thence to the paper machines.

The method and apparatus described effects the advantages above set forth, including an improvement in the character of finished stock, a material saving in the time required to produce finished stock, a considerable economy in labor and in the apparatus required to produce a predetermined amount of finished stock. The beaters themselves

and the Jordan engine may be of various constructions, these shown being illustrative of suitable structures for our purpose, and although we have shown and described particular forms, shapes and arrangements of the parts of the apparatus, and preferred details of the process, we do not desire to limit ourselves to the same as various changes may be made in the details of both apparatus and process without departing from the invention as set forth in the appended claims.

What we claim is:

1. The process of treating rags, consisting in cutting the rags into relatively small pieces, feeding said cut rags in substantially uniform stream upon the surface of a beater roll rotating at high speed, subjecting such cut rags combined with water to the action of the beater until reduced to half-stock condition, discharging the half-stock from the beater and into a half-stock chest, agitating the half-stock in said chest and separating heavy substances from the half-stock, pumping the half-stock from the chest and discharging it under high pressure upon a finishing beater roll rotating at high speed, subjecting such half-stock to the action of the finishing beater until the desired consistency is reached, discharging the stock from the finishing beater and passing it through a Jordan engine.
2. The process of treating rags in the production of pulp, comprising feeding the rags in a substantially uniform stream upon the surface of a beater roll rotating at high speed, subjecting such rags combined with water to the action of the beater until reduced to a half-stock condition, discharging the half-stock from the beater, propelling the half-stock under pressure on to the sur-

face of a rapidly revolving beater roll, and beating the half-stock until the desired consistency is reached.

3. In an apparatus of the class described, a rag cutter, a pair of half-stock beaters, means for directing cut rags from said rag cutter on to the upper surface of the beater roll of either of said half-stock beaters, a half-stock chest, means for discharging half-stock from either of said beaters into said half-stock chest, a pair of finishing beaters, and means for discharging half stock under pressure from the stock chest onto the upper surface of the beater roll of either of said finishing beaters.

4. The process of treating rags, consisting in cutting the rags into relatively small pieces, feeding said cut rags upon the surface of a beater roll rotating at high speed, subjecting such cut rags combined with water to the action of the beater until reduced to half-stock condition, discharging the half stock from the beater into a half-stock chest, agitating the half stock in said chest, pumping the half stock from the chest and discharging it under high pressure upon a finishing beater roll rotating at high speed, subjecting such half stock to the action of the finishing beater until the desired consistency is reached, and discharging the stock from the finishing beater and passing it thru a Jordan engine.

In witness whereof they have hereunto set their hands this 2nd day of February 1921.

J. H. HOWE.
CHARLES E. STEVENS.
